UNITED STATES PATENT OFFICE.

HENRY M. SHEER, OF QUINCY, ILLINOIS.

RADIATOR OR DRUM.

Application filed January 19, 1924. Serial No. 687,356.

To all whom it may concern:

Be it known that I, HENRY M. SHEER, a citizen of the United States, residing at Quincy, in the county of Adams and State 5 of Illinois, have invented certain new and useful Improvements in Radiators or Drums, of which the following is a specification.

My invention relates to an improved radiator or drum.

10 This device is intended for use with hovers and brooders, although it might be applied to other purposes where heat radiation is required.

15 The object is to exclude fine dust and explosive material from the flame or spark.

Dust or gas drawn to the burner flame in sufficient volume will necessarily become ignited, but it is impossible for the products 20 of combustion to ignite gas or dust unless the flame from the burner extends beyond the outer edge of the confines of the drum or radiator within which the burner is located.

It is the purpose of my invention to provide 25 against any such possibility, and to this end it consists in a spreader at the top for the escape of the products of combustion and a gauze screen across the bottom of the drum or radiator, and in this way provision is made for the unrestricted outlet for 30 the products of combustion, relieving the flame from any and all back pressure except what is produced by the air being drawn in through the fine screen at the bottom.

35 In the accompanying drawings:

Fig. 1 is a vertical section;

Fig. 2 is a plan view looking down into the air chamber.

The numeral 1 represents the air chamber 40 preferably made of cast metal with a skeleton bottom 2 providing air inlets 3. The air chamber 1 is preferably provided with a hole 4 in the bottom to receive the upper end of the oil inlet pipe 5 upon which it is

supported and a burner 6 is secured to the 45 extreme upper end of and is supplied by this pipe 5.

A disk or wire gauze 7 covers the entire bottom of the air chamber 1 to keep out dust and inflammable and explosive matter 50 which might otherwise be sucked in by the flame.

A spreader 8 at the top has its outer edge 9 crimped downwardly. The spreader is secured to the flange 10 at the top of the drum or radiator 11 by bolts 12 and spacers 13, thus providing a space 14 all around the top of the drum or radiator for the easy escape of the products of combustion. In this way, there is no back pressure upon 60 the flame, but as it rises and expands it has free issue all around the edge of the top so that there is little or no danger of ignition or explosion taking place due to sucking in inflammable or explosive matter 65 at the bottom, but as a precautionary measure against anything of the sort, the wire disk 7 may be employed at this point.

This is easily removable by lifting the ring 15 which rests above its edge, when 70 the wire gauze disk becomes clogged for the purpose of cleaning the same.

C is a diagrammatic representation of a canopy.

I claim:

The combination with a burner and an oil supply pipe therefor, of a hollow body having an annular inturned ledge therearound, a foraminated bottom integral with said ledge and hollow body, means secured to the supply pipe and engaging the foraminated bottom for supporting the hollow body, and a wire gauze covering for the foraminated bottom and being at a point below the burner.

In testimony whereof I affix my signature.

HENRY M. SHEER.
